[57] CLAIM

I claim the ornamental design for eyeglasses, as shown and described.

DESCRIPTION

FIG. 1 is a top perspective view of eyeglasses showing a first embodiment of my new design;

FIG. 2 is a bottom perspective view thereof;

FIG. 3 is a front elevational view thereof;

FIG. 4 is a rear elevational view thereof;

FIG. 5 is a right side elevational view thereof, the left side being a mirror image of the right side;

FIG. 6 is a top view thereof; and,

FIG. 7 is a bottom view thereof.
